(57) **CLAIM**

The ornamental design for a ring for hair dryer, as shown and described.

DESCRIPTION

FIG. 1 is a perspective view of a ring for hair dryer showing my new design;

FIG. 2 is the other perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.
